UNITED STATES PATENT OFFICE.

FRANK KARSITZ, OF BRIDGEPORT, CONNECTICUT, ASSIGNOR TO THE ACME SHEAR COMPANY, OF BRIDGEPORT, CONNECTICUT, A CORPORATION OF CONNECTICUT.

DESIGN FOR A HANDLE FOR SCISSORS AND SHEARS.

44,533.

Specification for Design.

Patented Aug. 19, 1913.

Application filed February 12, 1913. Serial No. 747,993. Term of patent 7 years.

To all whom it may concern:

Be it known that I, FRANK KARSITZ, a subject of the King of Hungary, residing at Bridgeport, county of Fairfield, State of Connecticut, have invented a new, original, and ornamental Design for a Handle for Scissors and Shears, of which the following is a specification, reference being had to the accompanying drawing, forming part thereof.

Figures 1 and 2 are elevations showing the opposite sides of my novel handle for scissors and shears.

I claim:

The ornamental design for a handle for scissors and shears, as shown.

FRANK KARSITZ.
